(57) **CLAIM**

The ornamental design for a respiratory gas humidifier, as shown and described.

DESCRIPTION

FIG. 1 is a front view of the invention in an application environment;

FIG. 2 is a perspective view of the invention;

FIG. 3 is a front view of the invention, the rear view being a mirror image thereof;

FIG. 4 is a side elevational view of the invention; and,

FIG. 5 is a side elevational view of the side opposite to that illustrated in FIG. 4.

The broken line showing is for illustrative purposes only and forms no part of the claimed design.
